2 Claims. (Cl. 323—1)

1

This application is a division of my copending U. S. application Serial No. 557,983, filed October 10, 1944, entitled "Intertube coupling circuit," assigned to the same assignee as the instant application.

This invention relates to a pulse operated relay circuit and has for an object to provide a circuit of the above type having novel and improved operating characteristics.

The invention relates more specifically to a circuit responsive to the coincidental reception of a pair of pulses at different input terminals and is adapted for use in a system of the type shown in my copending application Ser. No. 537,799, filed May 29, 1944, now Patent No. 2,449,819, for Radio control system, wherein pairs of pulses are transmitted over different channels in selected time sequences and are made available at the receiver in accordance with their sequence as coincidental pulses.

In one embodiment the present invention provides a relay circuit in which the coupling between a pulse amplifier tube and a relay tube is effected through a gaseous discharge tube which is normally non-conducting but becomes conducting in response to the received pulse. The relay tube becomes operative only when the intertube coupling path becomes conducting. The invention also provides a relay circuit in which the plate current remains substantially constant regardless of the state of operation of the relay.

Although the novel features which are characteristic of this invention are pointed out in the claims, the invention will be better understood by referring to the following description, taken in connection with the accompanying drawing in which a specific embodiment has been set forth for purposes of illustration.

In the drawings the figure is a schematic diagram of a relay circuit embodying the invention.

In the figure, a double triode tube 20 operates as a coincidental key tube which develops a series of voltage pulses in the plate resistor of the first section of double triode tube 30, operating as an amplifier. The plate of the second section of tube 30 is coupled by a gaseous conduction tube 41 to the grid of the first triode of a tube 50 the first section of which operates as a D. C. amplifier to operate a relay, and the second section of which is used to maintain constancy of current drain from the power supply source.

A battery 16 with the negative end grounded and connected to ground line 72 has its positive end connected to the negative end of battery 11,

and to cathode line 73. The battery 11 has its positive end connected to plate supply line 74. Between lines 73 and 72 are connected in series the ballast resistor 75 and the filaments of the three tubes 20, 30 and 50.

The tube 20 includes two triode units with common cathodes 21, two grids 22 and 23, and two plates 24 and 25. Tubes 30 and 50 are of similar construction with cathode 31 and 51, grids 32, 33 and 52, 53, and plates 34, 35 and 54, 55 respectively. The cathodes of all tubes are connected to line 73. Input to the system is from terminals 10, 11 and 12, of which terminal 12 is connected to ground line 72. Terminal 10 is connected through condenser 13 to the grid 22 of tube 20, which in turn is connected through resistor 15 to cathode line 73. Similarly terminal 11 is connected through condenser 14 to the grid 23 of tube 20 which in turn is connected through resistor 16 to the cathode line 73.

It is assumed that negative voltage pulses are impressed from two separate channels between terminals 10 and 12, and between terminals 11 and 12 respectively by a pulse circuit such for example as shown in my copending application above identified.

The plates 24 and 25 are connected together, and through resistor 26 to the plate supply line 74, also through resistor 27 to the grid 32 of tube 30, which in turn is connected through resistor 28 to the ground line 72. The plate 34 of tube 30 which is under control of grid 32 is connected through resistor 36 to plate supply line 74, also through condenser 37 to grid 33 of tube 50, which in turn is connected through resistor 38 and through condenser 39 to cathode line 73. The plate 55 of tube 50, under control of the grid 33, is connected through resistor 40 to the plate supply line 74, also to one terminal of a two terminal gaseous discharge type device 41 such as a neon lamp or a voltage regulator tube. The other terminal of the device 41 is connected through resistor 42 and condenser 43 to the ground line 72, and also through resistor 44 to the grid 52 of the tube 50. It will be understood that the device 41 will normally insulate the plate 55 from grid 52 and will conduct only during portions of the time when the system is operative.

The plate 54 under control of grid 52 is connected through the winding 56 of a relay 57 to the plate supply line 74. This relay is provided with an armature which normally is held away from the pole of the relay, but which is drawn to the pole when suitable direct current flows

through winding 56. Terminals 58 and 59 are connected to the armature and to a front contact for operating a work circuit not shown when the armature is pulled down toward the pole piece.

The plate 54 is also connected through resistor 60 to the grid 53, which in turn is connected through resistor 61 to ground line 72. The plate 55 under control of grid 53 is connected through resistor 62 to the plate supply line 74.

The constants of the system are so chosen that in the absence of signal inputs at terminals 10 to 12, a large voltage drop occurs in resistor 26, and the first section of tube 30 is biased far below cutoff so that no current flows in resistor 36, but that when signals are simultaneously impressed on the grids 22 and 23 making them both sufficiently negative to prevent current flow to the plates 24 and 25, the grid 32 comes to cathode potential so that current passes through resistor 36. Therefore a negative voltage pulse occurs at the plate 34 corresponding to the duration of overlap of the input pulses at the terminals 10 to 12. This pulse is transmitted through condenser 37, and by the action of resistor 38 and condenser 39 produces a negative pulse of saw tooth nature on the grid 33. Since in the absence of such pulses the grid 33 is at cathode potential, a large current flows through plate resistor 40, so that the potential of the plate 35 is low, and the voltage across device 41 is insufficient to cause gaseous conduction. With the circuit operative, the potential of the plate 35 increases to a high value and returns to the normal value at the pulse recurrent rate. The device 41 fires and extinguishes at the pulse rate so that current flowing from plate supply line 74, through resistor 40, and device 41 to resistor 42 and condenser 43 in a short time builds up a positive voltage across condenser 43, raising the negative terminal of 41 to above the potential of the cathode line 73. By use of resistor 44, the grid 52 is maintained at cathode potential although there may be some ripple across condenser 43 at the pulse recurrence rate. As a result, relay winding 56 passes current, and the armature closes contacts 58 and 59. When the pulses on the grid 33 cease, a steady state is brought about with device 41 not conducting, whereby the current in relay winding 56 drops and the relay contacts are opened.

In radio control devices it is sometimes helpful to maintain the plate supply substantially constant regardless of the operation of the relay. For this purpose, the resistors 60 and 61 directly couple the plate 54 to the grid 53. Adjustments are such that normally in the absence of signals the grid 53 is substantially at cathode potential, and a large current flows through plate resistor 62. When signals are received, the current to plate 54 increases, but due to the voltage drop in the relay winding 56, a bias voltage is im-

pressed on the grid 53, decreasing the current in resistor 62. It will be understood the normal current through relay winding 56 and resistors 60 and 61 will be much smaller than that required to operate the relay 57. By suitable design the current from the battery 71 is made substantially independent of the amount of relay current.

It will be noted that in the above system the control of the relay is positive in response to incoming coincidental signals. The coupling system including the tube 31 may, however, be applied to other uses where similar operating characteristics are required. The constant current features may also be applied to other circuits to maintain a substantially constant drain on the plate source.

Although a specific embodiment has been shown for purposes of illustration, various changes and adaptations may be made therein as will be apparent to a person skilled in the art. The invention is only to be limited in accordance with the scope of the following claims.

I claim as my invention:

1. A constant current circuit comprising a pair of space discharge devices having anodes and control elements, a source of anode current connected to supply said anodes, a load connected in series with the anode of one of said devices, signal means to cause a change in the amount of current passing through said load, and a direct coupling between said anode of said one device and the control element of the other of said devices connected to cause the space current of said other device to vary inversely as the space current of said one device so as to maintain a constant load on said source.

2. A constant current circuit comprising a pair of space discharge devices having anodes and control elements, a source of anode current connected to supply said anodes, a load connected in series with the anode of one of said devices to cause the voltage thereof to vary inversely with the space current, signal means to cause a change in the amount of current passing through said load, a direct coupling between said anode of said one device and the control element of the other of said devices to supply a control voltage to said element which causes the space current of said other device to vary inversely with the space current of said one device whereby a constant load is maintained on said source.
